US00D921893S

(12) **United States Design Patent** (10) **Patent No.:** **US D921,893 S**
(45) **Date of Patent:** **** Jun. 8, 2021**

(54) **T-SHAPED HANDLE FOR SURGICAL TOOLS**

(71) Applicant: **ECA Medical Instruments, Inc.**,
Newbury Park, CA (US)

(72) Inventors: **Michael J. Milella, Jr.**, Thousand
Oaks, CA (US); **Sarah Elizabeth**
Schaake, Centennial, CO (US); **Lane**
Aaron Hale, Thousand Oaks, CA (US)

(73) Assignee: **ECA Medical Instruments, Inc.**,
Newbury Park, CA (US)

(**) Term: **15 Years**

(21) Appl. No.: **29/713,238**

(22) Filed: **Nov. 14, 2019**

(51) LOC (13) Cl. **24-02**

(52) U.S. Cl.
USPC **D24/133**

(57) **CLAIM**

The ornamental design for a T-shaped handle for surgical tools, as shown and described.

DESCRIPTION

FIG. 1 is a top, front, right-side perspective view of a T-shaped handle for surgical tools showing the new design. FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings are included to show portions of the article that form no part of the claimed design.

1 Claim, 4 Drawing Sheets
